UNITED STATES PATENT OFFICE.

WILLIAM HADDEN, OF BROOKLYN, NEW YORK, AND HENRY VAN HOEVENBERGH, OF ELIZABETH, NEW JERSEY; SAID VAN HOEVENBERGH AS SIGNOR TO SAID HADDEN.

RAILROAD SIGNAL SYSTEM.

SPECIFICATION forming part of Letters Patent No. 307,760, dated November 11, 1884.

Application filed March 1, 1883. (No model.)

To all whom it may concern:

Be it known that we, WILLIAM HADDEN, of Brooklyn, in the county of Kings and State of New York, and HENRY VAN HOEVENBERGH, 5 of Elizabeth, in the county of Union and State of New Jersey, have invented a new and Improved Railroad Signal System, of which the following is a full, clear, and exact description.

Our invention relates to the class of railroad-s 10 signals employed in protecting a block or section of the road against occupation by more than one train at a time.

In our improved signal a continuous electric current is employed for holding the signal-banners in position to indicate safety, and the current is rapidly interrupted to weaken the power of the signal-magnet and allow the signal-banner to fall to indicate danger.

The invention consists in a peculiar combination of track-instruments, interrupters, and signal-magnets, whereby the entrance of the train at one end of the block sets in operation the interrupter, which allows the banner to fall, and continues to act automatically until 25 the train passes from the other end of the block, when the continuity of the current is re-established, and the signal-banners indicate that the track is clear.

Figure 1 is a diagrammatic representation of 30 our improved signaling system. Fig. 2 shows the track and circuit-connections.

In describing our improved signaling apparatus we shall, for the sake of clearness, refer to the parts of the apparatus as being in the 35 first, second, third, or fourth position, according to the direction of the train and position of the several parts. We have also indicated the opposite ends of the blocks in the drawings as "west" and "east."

In the first position, as shown in the drawings, the battery G is on the line from earth-connection E through circuit-breaking track-instrument C, wire 1, contact-point H' of armature-lever *a* of magnet A, armature-lever, wire 40 1, breaking track-instrument B, wire 1, signal-magnet D, switch F, wire 1, signal-magnet D', wire 1, circuit-breaking track-instrument B', wire 1, lever *a'*, back contact-point, H³, of armature-lever *a'* of magnet A', and wire 1, cir-

cuit-breaking track-instrument C' to earth-connection E'. By means of the battery G, working continuously through this circuit, the signal-magnets D and D' are made operative, holding signal-banners out of sight or in the safety position, as indicated in the drawings. In this 50 position the current from the battery G is shunted off from magnets A and A' by the back contacts, H' H³, of their respective armature-levers, so that the power of the battery upon the line is not lessened by the introduction of the 55 magnets A and A' into the circuit.

In the second position, when a train enters the section to be protected by this signal system from the west and operates the circuit-breaking track-instrument B, the circuit, as 60 described in the first position, is interrupted, and the armatures of the signal-magnets D and D' are released and the signal-banners are thrown to danger or in sight. The circuit from battery now flows through wire 2, magnet A, 65 wire 2, and thence to E, as before. The effect of this change of circuit is as follows: Magnet A, becoming operative, attracts its armature, and the front contact-points, H, will be brought together, where they will remain as long as the 70 circuit-breaking track-instrument B remains open. When the said circuit-breaking track-instrument B becomes closed, the current will be shunted off from magnet A through wire 1, front contacts, and armature-lever *a* of magnet 75 A, wire 1, and track-instrument B. This will release the armature of magnet A, and it will be drawn backward by the retractile force of the spring *b*, connected with the armature-lever *a*; but when the front contacts, H, become 80 separated the current will again flow through magnet A, bringing forward the armature before the back contacts, H', have come together, and a vibratory motion of the armature-lever will continue until stopped by a further operation, hereinafter described. The effect of this 85 vibratory motion of the armature-lever of magnet A will be to so reduce the power of the battery-current upon the whole line as to render the signal-magnets D and D' inoperative, 90 thus continuing the signals at danger or in sight. When in the progress of the train toward the east the circuit-breaking track-in- 95

strument C' is reached and operated, the current from battery is temporarily interrupted, permitting the armature-lever of magnet A to be retracted, so as to bring the back contact-points, H', together, thus cutting the current off from magnets A and stopping the vibratory movement of its armature-lever. This operation will again throw the full and uninterrupted power of the battery upon the line, which will operate the signal-magnets B and B', bringing the signals to safety or out of sight, thus reforming the circuit, as shown in first position in the drawings, and as described above.

15 In the third position, when the system is operated by a train entering from the east end, an exact repetition of effects already described is produced, except that the armature-lever of magnet A' becomes vibratory, and continues 20 so until circuit-breaking instrument C is actuated, with the results as already described.

In the fourth position, when it is desired to operate the signal-magnets from an intermediate point by hand, all that is necessary is to 25 break the circuit by means of the switch F, when all of the armatures of signal-magnets will be released and the signals thrown to danger or in sight. By replacing the switch to its original position the full power of the battery will again operate the signal-magnets, throwing the signals to safety or out of sight.

The switch F and circuit-breaking track-instruments B B' C C' are of the usual well-known form, and will therefore require no description.

30 Having thus described our invention, we

claim as new and desire to secure by Letters Patent—

1. In a circuit for an electric railroad signal system, the combination of a rheotome, two circuit-breaking track-instruments, one or 40 more signal-magnets, and the circuit-wires, as herein specified.

2. In an electric railroad signal system, an electric magnet, and a circuit-breaking track-instrument communicating with the battery 45 and main line, and a circuit shunting the electro-magnet and communicating with the battery and main line, in combination with a vibratory armature-lever having front and back contacts and a circuit-breaking instrument, 50 the said vibratory lever and track-instrument being in the shunt-circuit, as specified.

3. In an electric railroad signal system, the electro-magnets A A', circuit-breaking track-instruments C C' in the main circuit, the shunts, 55 including the vibratory levers a a', and track-instruments B B', the signal-magnets D D', and one or more switches, F, in combination with electrical connectors, substantially as herein shown and described.

4. In an electric railroad signal system, the combination of the circuit-operating magnet A, armature-lever a, contacts H H', track-instruments B B', signal-magnets D, and their respective circuit-wires, as herein specified.

WILLIAM HADDEN.

HENRY VAN HOEVENBERGH.
